UNITED STATES PATENT OFFICE.

THOMAS M. BRINTNALL, OF OAKLAND, AND NELSON R. DOOLITTLE, OF BERKELEY, CALIFORNIA.

FIREPROOF ATTACHMENT FOR VAULTS.

No. 902,050.

Specification of Letters Patent.

Patented Oct. 27, 1908.

Application filed November 20, 1907. Serial No. 402,949.

To all whom it may concern:

Be it known that we, THOMAS M. BRINTNALL and NELSON R. DOOLITTLE, citizens of the United States, residing at Oakland and Berkeley, respectively, in the county of Alameda and State of California, have invented certain new and useful Improvements in Fireproof Attachments for Vaults, of which the following is a specification.

10 The present invention relates to an improved fireproof attachment for use in connection with safe deposit vaults, and structures of a similar character, the object of the invention being mainly to protect the entrance door to the vault, and more especially the complex and expensive burglar-proof lock mechanism carried thereby from injury in case of fire.

20 To comprehend the invention reference should be had to the accompanying sheet of drawings, wherein is illustrated a broken horizontal sectional view of an ordinary safe deposit vault with the improved fireproof attachment applied to the face thereof for the 25 protecting of the door of the vault and its lock mechanism against the action of fire.

30 In the drawings, the numeral 1 is used to designate the front steel wall of the vault to be protected, and 2 the entrance door thereto, which carries and supports the complex and expensive lock mechanism 3. These parts are of the usual construction utilized in connection with the erecting of safe deposit vaults, and vaults generally.

35 The fireproof attachment comprises a light metallic body structure 4, secured to the face or wall 1 of the vault so as to project therefrom a given distance at each side of the door 2, in order to form a vestibule 5. The said 40 metallic frame structure 4 is surrounded by an outer wall 6 composed of concrete, the thickness of which is sufficient to offset the action of heat. The concrete wall 6 is formed with an entrance-way, which is closed 45 by the door 7, said door in the present case constituting an outer door for the vault. This door is composed of the inner and outer face plates 8—9, which are separated by a concrete wall or bed 10, which wall or bed is 50 of a thickness approximately equal to the thickness of the concrete wall 6, of the vestibule 5.

In the outer door construction shown, the face plates 8—9 are connected by the union-bolts 11, which bolts extend through the con-

crete wall or bed 10 of the said door 7, and in addition to uniting the said face plates, they serve to support and hold to the face of the inner plate 8, the frame 12, within which work the lock bolts 13. The outer ends of 60 the lock bolts 13 when thrown to lock the outer door 7, engage the flanged ends 14 of the vestibule frame 4, and against such flanged ends of the said vestibule frame rests or bears the inner face plate 8 of the door 7, 65 when the door is closed.

The concrete wall or body 6, and likewise the concrete wall or bed 10 of the outer door 7, we reinforce and strengthen by means of the rods 15, which are disposed horizontally 70 and vertically through the body of concrete, being inserted during the forming of the concrete walls. However, it is obvious that any suitable form of reinforcing material for the concrete may be utilized in place of the reinforcing rods or bands 15.

The inner vault door 2 swings on the crane hinge 16, while the outer vestibule door 7 swings on the crane hinge 17, which said 80 hinges are of the usual construction.

The metallic door and jamb frames generally employed in connection with door constructions are omitted, the steps 18 of the door 7, and the steps 19 of the door frame portion of the vestibule wall 6 being formed 85 during the molding of the concrete constituting the wall 6, and the wall or bed 10 of the door 7.

In the edge of the door frame portion of the concrete wall 6, are embedded the anchor 90 clips 20, with which clips register the anchor clips 21, embedded in the concrete wall or bed 10, when the door 7 is closed.

It will be observed that the vestibule 5, when the door 7 is closed, forms an air chamber 95 for the inner door 2, which protects the said door and its burglar-proof lock mechanism from the disastrous effect of heat, where the vault is exposed to the action of fire.

The heavy concrete surrounding wall 6, together with the concrete wall 10 of the door 7 being a non-conductor, perfect heat insulation is obtained; hence full protection is given to the door proper of the protected vault, and inasmuch as the outer door and the concrete body for the vestibule we form without the usual metallic door and jamb frames, heat induction to the interior of the vestibule 5 is provided against.

The described fireproof attachment is sim- 110

ple of construction, inexpensive as to manufacture, and insures perfect protection to the vault door and its burglar-proof lock mechanism against the effect of heat generated by a surrounding fire.

Having thus described the invention, what is claimed as new and desired to be protected by Letters Patent is—

1. A fireproof attachment for the door of a deposit vault and in combination with the vault, a metallic vestibule frame secured to the face of the vault to encompass the door thereof, of a concrete wall embracing the vestibule frame, and a door for closing the entrance-way to the vestibule, the same comprising face plates separated by a concrete wall of approximately the thickness of the vestibule wall.

2. A fireproof attachment for the door of a deposit vault and in combination with the vault, a vestibule frame secured to the face of the vault to encompass the door thereof, of a concrete wall embracing the vestibule frame,

of reinforcing material embedded within the concrete wall, and a door for closing the entrance-way to the interior of the vestibule, the same comprising face plates separated by a wall of reinforced concrete.

3. The means of protecting the door and burglar-proof lock mechanism of a safe deposit vault, which consists in surrounding the door of the vault to be protected by a vestibule having its walls composed of concrete, and closing the entrance-way of the vestibule by a door consisting of face plates separated by a wall of concrete, forming a closed air chamber around the door of the vault when the door to the vestibule is closed.

In testimony whereof we have signed our names to this specification in the presence of two subscribing witnesses.

THOMAS M. BRINTNALL.
NELSON R. DOOLITTLE.
